TOILET BOWL BRUSH

Leidy G. Scholl, Lansdale, Pa.

Application September 28, 1956, Serial No. 43,134

Term of patent 14 years

(Cl. D9—2)

I claim:

The ornamental design for a toilet bowl brush, as shown.
